US00D768419S

(12) **United States Design Patent** (10) Patent No.: **US D768,419 S**
(45) Date of Patent: **** Oct. 11, 2016**

(54) **TABLE**

(71) Applicant: **NARDI SPA**, Chiampo (IT)
(72) Inventor: **Raffaello Galiotto**, Chiampo (IT)
(**) Term: **15 Years**
(21) Appl. No.: **35/500,307**
(22) Filed: **Nov. 4, 2015**

(80) **Hague Agreement Data**

Int. Filing Date: **Nov. 4, 2015**
Int. Reg. No.: **DM/088232**
Int. Reg. Date: **Nov. 4, 2015**
Int. Reg. Pub. Date: **Nov. 27, 2015**
(51) LOC (10) Cl. **06-03**
(52) U.S. Cl. **D6/691.6**
